US00D615957S

(12) **United States Design Patent**
Ju et al.

(10) **Patent No.:** **US D615,957 S**
(45) **Date of Patent:** **** May 18, 2010**

(54) **WIRELESS INTERNET PHONE**

(75) Inventors: **Tai-Hyung Ju**, Seoul (KR);
Kyung-Hoon Lee, Seoul (KR);
Sang-Sung Woo, Seoul (KR); **Bum-Ho**
Chun, Seoul (KR); **Tae-Hun Kim**, Seoul
(KR)

(73) Assignee: **Samsung Electronics Co., Ltd.** (KR)

(**) Term: **14 Years**

(21) Appl. No.: **29/342,147**

(22) Filed: **Aug. 19, 2009**

(30) **Foreign Application Priority Data**

May 26, 2009 (KR) 30-2009-0022559

(51) **LOC (9) Cl.** **14-03**

(52) **U.S. Cl.** **D14/147**

(57) **CLAIM**

The ornamental design for a wireless internet phone, as shown and described.

DESCRIPTION

FIG. 1 is a perspective view of a wireless internet phone, showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a perspective view thereof, wherein the environmental structure shown in broken lines forms no part of the claimed design.
